UNITED STATES PATENT OFFICE.

JOHN B. FITZPATRICK, OF NEW YORK, N. Y.

COLLAR SUPPORT.

1,412,028.

Specification of Letters Patent.

Patented Apr. 4, 1922.

Application filed April 8, 1921. Serial No. 459,685.

To all whom it may concern:

Be it known that I, JOHN B. FITZPATRICK, a citizen of the United States, residing at New York city, borough of Manhattan, in 5 the county and State of New York, have invented a certain new and useful Collar Support, of which the following is a specification.

This invention is a support for collars and 10 the object of the invention is to provide a device whereby collars may be properly supported at the front of the neck in such manner as to preclude sagging or drooping thereof, so that the collar will, at all times, be 15 maintained in upstanding position and appear neat and aesthetic.

Many devices have been heretofore employed for supporting the front of the collar, and, more particularly, collars of the soft 20 fold over variety. The most common of these expedients embodies stiffening members, either permanently or detachably associated with the fold over portion of the collar, either by positioning rigid members between 25 the plies of the fold over portion or by forming pockets into which rigid members are adapted to be removably inserted. It has also been suggested to stiffen the neck band of the collar by incorporating therein rigid 30 members, but none of the prior devices, so far as I am aware, satisfactorily fulfills the requirements for the reason that the supporting and stiffening means finds insufficient support in the collar construction, so that 35 even though the stiffening means is capable of distending the portion of the collar with which it is associated, the collar droops bodily and becomes unattractive in appearance.

With these considerations in mind, the 40 present invention aims to support a collar from the shirt stud, so that a firm and fixed support may be provided, which will preclude bodily sagging of the collar, while, in the case of soft collars, the comfort inherent 45 in the pliancy of such collars is preserved.

The invention may partake of various forms, but in all of these forms, the underlying principle remains the same. That is to say, means is provided for engaging or 50 gripping the shank of the collar button and with this means is associated wings or upstanding supporting members, which engage with the fold at the upper portion of the collar, and serve to maintain the collar in dis- 55 tended condition.

Features of the invention, other than those

specified, will be apparent from the herein- 60 after detailed description and claims, when read in conjunction with the accompanying drawings.

The accompanying drawings illustrate 65 different practical embodiments of the present invention, but the constructions therein shown are to be understood as illustrative, only, and not as defining the limits of the invention.

Figure 1 shows the preferred form of collar support of the present invention.

Figure 2 is a side elevation of the construction shown in Figure 1.

Figure 3 is an enlarged detail of construction entering into the device of Figure 1.

Figure 4 is a plan view of the detail shown in Figure 3.

Figure 5 illustrates a slightly modified 75 form of the invention associated with a collar.

Figure 6 is a fragmentary showing of a further modified form of the invention.

Figure 7 illustrates another form of the 80 invention;

Figure 7^a is an edge view of the construction shown in Figure 7; and

Figure 8 shows the simplest form of 85 which the invention may partake.

Referring first to the construction as 90 shown in Figures 1 to 4, inclusive, 1 designates a standard which may be conveniently formed in a casting of substantially inverted Y-shape. The legs of the standard 95 are spaced apart to permit the standard to straddle the shank of a collar button and in the intervening space a wire clip or yoke 2 is mounted for pivotal movement. The yoke 2 is preferably formed of spring wire whereby it is adapted to be forced down over the shank of the collar button and firmly grip the same for the purpose of mounting the standard upon the button.

The standard is preferably off set as shown 100 in Figure 2 and is provided at its top with a pocket 3 adapted to receive the shank 4 of a wire loop 5. In practice, this wire loop may be formed of a single piece of wire bent into the desired shape and provided at its end 105 with shanks 4 which seat in the pocket 3 and are locked in place therein by a set screw 6, which threads into the standard and bears against the shanks of the loop as clearly shown in Figures 1 and 2. When a single 110 wire is used for the formation of the loop 5, it is adapted to be bent as occasion may re-

quire into such shape as to adapt it to properly fit between the neck band and the fold over portions of the collar and engage with the fold at the joining of the two parts, in such manner as to snugly fit into said fold for the purpose of properly supporting the collar in upstanding position. However, as shown in Figures 1 to 4, the loop 5 is formed in two parts, which are joined together by a set screw 7. Figures 3 and 4 clearly illustrate the manner in which the binding of the wire sections is accomplished and from these views, it will be understood that the end of one wire section is bifurcated at 8 to receive a reduced portion 9 formed on the end of the other wire section. The screw 7 threads through the bifurcated end of the first section and serves to tightly clamp the reduced end of the other section in place. In practice, the coacting surfaces of the two sections may be serrated, so that when the parts are clamped together, pivotal movement of the section provided with a reduced end upon the screw 7 will be precluded.

When the loop 5 is formed in two sections with the ends secured together as described, the set screw 7 may be loosened to permit of adjustment between the sections in such manner as to bring the upper portion of the loop into substantially the same configuration as the fold of the collar, with which said portion of the loop is intended for co-operation, so that when the device is associated with the collar, the collar is not forced out of shape, but it will be supported in a perfectly natural manner.

When a device constructed as described is associated with a collar with the yoke 2 embracing the shank of the collar button and the loop 5 positioned between the neck band and the fold over portion thereof, and engaging the fold between these parts, it will appear that the collar is supported independently of the neck band or fold over portion and directly from the collar button which furnishes a firm support or anchorage for the device, so that the slightest sagging of the collar is precluded. The fact that the loop extends to either side of the front opening of the collar will preclude a turning of the device on the collar button and said device will be maintained in proper concealed position, until released from the collar button by the wearer, preliminary to removing the collar.

In Figure 5, a slightly modified form of construction is shown as associated with a collar. This construction differs from the construction of Figure 1 in two particulars, namely, instead of using a set screw 6 to lock the shanks of the loop to the standard 1, a depression 10 is formed in the standard 1 after the shanks have been positioned in the socket and the depressing of the exterior of the standard serves to indent the interior of

the pocket and tightly clamp the shanks in position. A further difference between the two constructions is that in Figure 5 the central upper portion of the loop is curved downwardly as at 11, so that that portion of the loop which passes across the open front of the collar will be sufficiently low as to be concealed by the knot of a neck tie 12. The loop of the construction of Figure 5 may be made in one or two sections after the manner described with reference to the construction of Figure 1.

Figure 5 graphically illustrates the manner in which the collar is supported by a device embodying this invention and it will be clearly seen from this figure, wherein the collar button bears the reference numeral 13 that the device is supported on the button in such manner as to efficiently maintain the collar in upstanding position.

In Figure 6, a further modified form of the invention is shown, wherein, instead of employing a wire loop to support the collar, a sheet of celluloid or other suitable rigid material 5^a is employed. This sheet of celluloid is provided with arms, shaped in any suitable manner to engage the fold of the collar and with a depending portion 4^a by means of which it is associated with a standard 1^a. In this construction, the upper portion of the standard is slotted in lieu of the pocket and the depending portion 4^a is adapted to seat in the slot and be locked in position by a set screw 6.

In another modified form of the invention, as illustrated in Figures 7 and 7^a, the standard 1^b is formed of a slightly different shape and is transversely slotted in its upper portion to receive the inner ends of two arms 5^b which may conveniently be formed of celluloid or other suitable rigid material. The arms 5^b are, in turn, provided with slots 14, through which set screws 15 pass. These set screws are threaded into the standard 1^b and are adapted when tightened to clamp the arms 5^b in position. The standard 1^b is provided with a yoke 2 of the character hereinbefore described and the top of the standard is preferably formed with a concave edge 16 corresponding to the shape of a collar at the front thereof. The upper edges of the arms 5^b are similarly shaped, so that when the device is positioned to co-operate with the collar, the upper edge of the standard as well as the upper edges of the arms will closely conform to the shape of the collar and support the same without distortion. It will be noted, however, that when the set screws 15 are loosened, the curvature of the upper edge of the device may be changed to bring the parts into proper conformity with the collar and in the event that the device is to be associated with a high collar, the arms 5^b may, by virtue of the slots 14, be shifted in an upward direc-

tion, so that the arms will properly support the collar and the set screws 15 thereupon tightened to lock the parts firmly in position for a collar of such height.

5 It is common for wearers of soft collars to use pins, clasps or other means for holding down the free ends of the fold over portion of the collar and this is particularly true in collars having long points. The use of such 10 adjuncts may be dispensed with when the present invention is employed by rigidly mounting on the arms 5^b small sharp pointed hooks 17. These hooks may be secured in place in any suitable way and may be engaged by the fold over portion of the collar 15 to hold down the points.

It will be understood in this connection that the hooks or pins 17 are not restricted in their use to the construction of Figure 7, 20 but that they may be associated with any form of which this invention may partake.

In Figure 8 of the drawings, I have illustrated one of the simplest forms of which the invention is capable of embodiment. In 25 this showing, the device is in the form of a sheet of some rigid or semi-rigid material such for example as celluloid. From such material, the device may be stamped out to embody a depending yoke portion 18 having 30 a slot 2^a formed therein to receive the shank of a collar button, and at the top of which depending portion, the device is formed with laterally extending arms or wings 5^c.

Having thus fully described the invention, 35 what I claim as new and desire to secure by Letters Patent is:

1. A device of the character described embodying a rigid standard bifurcated to provide two spaced legs, a yoke positioned 40 between and pivoted to the legs of the standard and adapted to seat on the shank of a collar button for the purpose of pivotally mounting the standard on the collar button to permit the standard to adapt 45 itself to movements of the neck, and wings mounted on the standard and adapted to engage with the fold of the associated collar to support the collar in upstanding position.

2. A device of the character described 50 embodying a standard, a yoke pivoted to the standard and adapted to seat on the shank of a collar button for the purpose of pivotally mounting the standard on the collar button to permit the standard to adapt itself 55 to movements of the neck, and a pair of flaps pivotally mounted on the standard and adapted to be pivotally moved to engage with and conform to the fold of a collar for

the purpose of supporting the collar in up- 60 standing position.

3. A device of the character described embodying a standard, a yoke pivoted to the standard and adapted to seat on the shank of a collar button for the purpose of pivotally mounting the standard on the collar 65 button to permit the standard to adapt itself to movements of the neck, a pair of diverging wings pivoted to the standard and adapted to be shifted into a position to conform to and engage with the fold of an associated collar, and means for locking the wings against pivotal movement after they have been adjusted.

4. A device of the character described 70 embodying a standard, a yoke pivoted to the standard and adapted to seat on the shank of a collar button for the purpose of pivotally mounting the standard on the collar button to permit the standard to adapt itself to movement of the neck, a pair of diverging wings mounted on the standard for vertical adjustment and also for pivotal movement, whereby the wings may be vertically adjusted to compensate for collars of different heights and pivotally adjusted to 75 engage with and conform to the fold of the associated collar.

5. A device of the character described 80 embodying a standard, a yoke pivoted to the standard and adapted to seat on the shank 90 of a collar button for the purpose of pivotally mounting the standard on the collar button to permit the standard to adapt itself to movement of the neck, a pair of diverging wings mounted on the standard for vertical 95 adjustment and also for pivotal movement, whereby the wings may be vertically adjusted to compensate for collars of different heights and pivotally adjusted to engage with and conform to the fold of the associated collar, and means for locking the wings rigidly to the standard after they 100 have been adjusted.

6. A device of the character described, 105 embodying a standard provided with an offset and bifurcated at its lower portion, a yoke extending across the bifurcated portion and adapted to seat on the shank of a collar button, and a pair of lateral extensions associated with the upper portion of the standard and adapted to engage with the fold of a collar for the purpose of supporting the collar from the collar button.

In testimony whereof, I have signed the foregoing specification.

JOHN B. FITZPATRICK.
